SLING

Frank E. Stahl, Tonawanda, Alfred Cotesworth, Kenmore, and Erford E. Robins, Tonawanda, N. Y., assignors to Columbus McKinnon Chain Co., Tonawanda, N. Y., a corporation of New York

Application March 1, 1933, Serial No. 659,112

6 Claims. (Cl. 294—75)

Our invention relates in general to slings, and more particularly to that type of sling used in the handling of sugar-cane. Although the invention is designed particularly for handling sugar-cane, it is obvious that it may be used for handling bundles of other materials with equal efficiency.

It is well known to those skilled in the art that a ring at one end of the chain is usually used with such a sling, as hereinbefore described, but that the ring many times breaks in use, and that unless the one or more links at the free end of the chain can be fastened to the sling, unavoidable delays are caused by the making of necessary repairs.

One of the principal objects of our invention has been to provide a sling having a hook which may be used with a ring or not, as desired.

Another object has been to provide a sling having a hook on which it shall be impossible for the links of the chain to catch when the chain is released, whether the chain is fastened to the hook by means of a ring or one or more of the links of the chain.

Another object has been to provide a sling so constructed that the chain may be easily drawn therethrough when supporting the load so as to take up all slack in the chain, and one which shall securely lock the chain against passage through the sling in opposite direction, except when released.

The above objects and advantages have been accomplished by the device shown in the accompanying drawing, of which:

Fig. 1 is a sectional elevation of my device, and is taken on line 1—1 of Fig. 2.

Fig. 2 is a plan view thereof.

Fig. 3 is a transverse, sectional elevation thereof, and is taken on line 3—3 of Fig. 1.

Fig. 4 is a front elevation of the device showing the hook.

Fig. 5 is a sectional, plan view of the hook, and is taken on line 5—5 of Fig. 1.

The body of our device is formed from two side plates 10 and 11, held together by any suitable means. At one end of the body there is provided a guide roller 12 with which the chain 13 is engageable. As shown in Fig. 1, the chain passes over and in contact with the inner face of the guide roller and around under the same, whence it is passed to and around the bundle of sugar-cane or other material being handled. The guide roller is provided with a circularly shaped groove 14 which engages those links which have their planes at right angles to the axis of the guide roller, while the peripheral flanges 15 act as

abutments for the alternate links of the chain. Hereinafter we will refer to the links which have their planes at right angles to the axis of the guide roller as longitudinal links, and to the alternate links which are at right angles to the longitudinal links as crosswise links.

Arranged in front of the guide roller and slidably held in the body is a chain plunger 20. This plunger is slidably mounted in suitable bearings 21, 22, and 23. A helical spring 24 (see Fig. 65) is mounted in a recess 25 formed in the plunger and serves to keep the same urged toward the guide roller. This plunger is provided at its forward end with a head 26 formed on its forward face with surfaces 27 and 28. A forwardly projecting, central portion 29 lies between the surfaces 27 and 28 and is of substantially the same width as the width of the groove 14 of the roller. A semi-circular recess 30 is formed in the forward face of the portion 29 which engages with the longitudinal links as they are passing through between the plunger and the roller. Under normal conditions, or when the chain is not being passed through the sling, the crosswise link 31 is held between the surfaces 27 and 28 of the plunger head 26 and the peripheries 15 of the guide roller. When in such position the longitudinal link 32 immediately above the crosswise link 31 rests upon the head of the plunger. The head of the plunger is provided with a curved indentation 33 on its upper surface with which the bottom of the link 32 engages. The plunger, therefore, acts as a stop to prevent the chain from passing downwardly through the sling.

The forward surface of the head 26 of the plunger is undercut, as shown in Fig. 1, and is provided with a groove 34 to accommodate the upper end of the link 35. Due to the inclined, forward surface of the head 26 of the chain plunger, the plunger will be forced backwardly against the tension of the spring when the chain is moved upwardly through the sling to take up the slack or to adjust the chain to the size bundle to be handled. During such movement, the links of the chain will be held by the guide roller and the head of the plunger in the positions shown in Fig. 1 and whenever a crosswise link comes to a stop in front of the plunger 20, the plunger will automatically engage such link and the link immediately above it and thus serve to hold the chain in fixed position against downward movement. An operating arm 36 extends upwardly from the plunger 20, whereby the same may be actuated. This arm is provided prefer-

ably with a slot 37 for engagement with a finger or hook as desired.

Arranged at the opposite end of the body of the sling is the hook 40 of my device. This hook 5 is pivotally mounted between the plates 10 and 11 of the body upon a pin 41. It is provided with a lip 42 and formed with a ring engaging surface 43. The forward side of the hook is provided with interspaced flanges 44 and 45, thus forming a 10 centrally arranged recess 46 for engagement with one of the longitudinal links 49. Formed in the flanges 44 and 45 of the hook are two circular recesses 50 which lie in a plane at right angles to the plane of the recess 46 and with 15 which the crosswise link 51 is engageable to hold the end of the chain securely in the hook when the end of the chain is used instead of the ring (not shown) hereinbefore referred to. The hook is provided with an inwardly extending heel 52 20 having a latch 53 at its extreme inner end. A hook plunger 54 is slidably mounted within the side plate 11 of the body of the device and the forward end of this plunger is engageable with the latch 53 to prevent the counter-clockwise 25 movement of the latch. The plunger 54 is carried in suitable bearings 55, 56, and 57 and it is provided with a recess 58 in which is mounted a helical spring 59, whereby it is kept normally in the position shown in the drawing.

30 Carried between the side plates is a release lever 60. This lever is pivotally mounted upon a pin 61 and has a depending cylindrical portion 62 which is disposed between upstanding, interspaced ears 63 carried by the hook plunger. The 35 upper end 64 of the lever is provided with an aperture 65 with which a bar may be engaged to move the plunger backwardly to release the latch 53 of the hook. The hook is provided with an overhanging lip 66 which engages the edge of 40 the plate 11 of the body to limit further inward movement of the hook.

When our device is to be put into use, sufficient chain is passed between the chain plunger 20 and guide roller 12 to accommodate the size of bundle being handled and the free end is passed about the bundle, and if desired the ring usually furnished at the end of such chain may be engaged with the surface 43 of the hook 40. If no ring is provided at the end of the chain or 45 if it is desired not to use it, any of the links near the end of the chain may be engaged with the recesses 46 and 50 in the face of the hook, as shown in Figs. 1 and 5. When the ring or the links at the end of the chain have been engaged 50 with the hook, and the derrick raises the chain, the slack in the chain will be taken up by passage of the chain between the head 26 of the chain plunger 20 and the guide roller 12. During such taking-up movement, the chain plunger 60 will be forced back and forth in its bearings against the tension of the spring 24 as each of the longitudinal links is passed between it and the roller. Since the single chain carries the load being lifted, it is not necessary that the reverse 65 movement of the chain through the sling be prevented, but should one of the crosswise links come to a stop opposite the chain plunger when the load is being supported, the plunger would engage the opening of such link. When it is desired to release the load, a suitable rod (not shown) may be engaged with the release lever and is operated so as to withdraw this lever from engagement with the latch 53 of the heel 52 of the hook. When so released, the hook 40 will 70 be permitted to rotate in a counter-clockwise di-

rection under the weight of the load and the end of the chain, whether engaged with the hook by means of its links or by means of a ring will be freely disconnected therefrom. When the links of the chain are used to engage the hook, the chain will be freely disengaged from the hook without possibility of any of the links catching on any portions of the hook.

Obviously, some modifications of the details herein shown and described may be made without departing from the spirit of our invention or the scope of the appended claims, and we do not, therefore, wish to be limited to the exact embodiment herein shown and described, the form shown being merely a preferred embodiment thereof.

Having thus described our invention, what we claim is:

1. The combination with an open link chain, of a sling comprising a body, a guide roller at one end of the body for engagement with the upward pass of the chain, a hook pivotally mounted at the opposite end of the body, the hook being formed with an unbroken ring engaging portion and with recesses in its forward surface for engagement with the links of the free end of the chain, and latch means for releasably holding the hook in locked position.

2. The combination with an open link chain, of a sling comprising a body, a guide roller at one end of the body for engagement with the upward pass of the chain, a hook pivotally mounted at the opposite end of the body, the hook being formed with an unbroken ring engaging portion, interspaced flanges formed at the forward side of the hook for the accommodation of longitudinally arranged links of the chain, the flanges being formed with recesses for the engagement of crosswise links of the chain, and latch means for releasably holding the hook in locked position.

3. The combination with an open link chain, of a sling comprising a body, a guide roller at one end of the body for engagement with the upward pass of the chain, a hook pivotally mounted at the opposite end of the body, the hook being formed with an unbroken ring engaging portion and with recesses in its forward surface for engagement with the links of the free end of the chain, latch means for releasably holding the hook in locked position, and a chain plunger mounted for reciprocating movement in the body and coacting with the guide roller to lockingly hold the upper pass of chain in position.

4. The combination with an open link chain, of a sling comprising a body, a guide roller at one end of the body for engagement with the upward pass of the chain, a hook pivotally mounted at the opposite end of the body, the hook being formed with an unbroken ring engaging portion and with recesses in its forward surface for engagement with the links of the free end of the chain, and a hook plunger mounted for reciprocating movement in the body and engageable with the hook for releasably holding the same in its locked position.

5. The combination with an open link chain, of a sling comprising a body, a guide roller at one end of the body for engagement with the upward pass of the chain, a hook pivotally mounted at the opposite end of the body, the hook being formed with an unbroken ring engaging portion and with recesses in its forward surface for engagement with the links of the free end of the chain, a chain plunger mounted for reciprocating movement in

the body and coating with the guide roller to lockingly hold the upper pass of chain in position, and a hook plunger mounted for reciprocating movement in the body and engageable with the hook for releasably holding the same in its locked position.

6. The combination with an open link chain, of a sling comprising a body, a guide roller at one end of the body for engagement with the upward pass of the chain, a hook pivotally mounted at the opposite end of the body, the hook being formed with an unbroken ring engaging portion, interspaced flanges formed at the forward side of the hook for the accommodation of longitudi-

nally arranged links of the chain, the flanges being formed with recesses for the engagement of crosswise links of the chain, a chain plunger mounted for reciprocating movement in the body and coating with the guide roller to lockingly hold the upper pass of chain in position, and a hook plunger mounted for reciprocating movement in the body and engageable with the hook for releasably holding the same in its locked position.
